(57) **CLAIM**

The ornamental design for a set of components for a patient repositioning system, as shown and described.

DESCRIPTION

FIG. 1 is a top left perspective view of a bed, patient and a set of components for a patient repositioning system showing our new design;

FIG. 2 is top left perspective view of the set of components for a patient repositioning system of FIG. 1;

FIG. 3 is a left side exploded view of the set of components for a patient repositioning system of FIGS. 1-2;

FIG. 4 is a right side exploded view of the set of components for a patient repositioning system shown in FIGS. 1-3;

FIG. 5 is a top exploded view of the set of components for a patient repositioning system shown in FIGS. 1-4;

FIG. 6 is a bottom right exploded view of the set of components for a patient repositioning system shown in FIGS. 1-5;

FIG. 7 is a bottom left perspective and exploded view of the set of components for a patient repositioning system shown in FIGS. 1-6; and,

FIG. 8 is a top left perspective view of a bed equipped with a set of components for a patient repositioning system showing our new design.

The broken lines seen in FIGS. 1 and 8 showing a bed and a human form are included for the purpose of illustrating environment and form no part of the claimed design. The broken lines seen on portions of the set of components for a patient repositioning system represent stitching and form part of the claimed design.

1 Claim, 8 Drawing Sheets
